UNITED STATES PATENT OFFICE.

GUY CROWLEY, OF HARTFORD, CONNECTICUT.

DESIGN FOR A TIRE.

49,952.

Specification for Design.

Patented Nov. 28, 1916.

Application filed September 17, 1914. Serial No. 862,242. Term of patent 14 years.

To all whom it may concern:

Be it known that I, GUY CROWLEY, a citizen of the United States, residing in the city of Hartford, county of Hartford, and State of Connecticut, have invented a new, original, and ornamental Design for Tires, of which the following is a specification, reference being had to the accompanying drawings, in which—

Figure 1 represents a side elevation; and

Fig. 2 a plan view of a portion of a tire showing my design.

I claim:

The ornamental design for a tire as shown.

GUY CROWLEY.
